CLAIM

The ornamental design for a keyboard including a control bar, as shown and described.

DESCRIPTION

FIG. 1 is a front, bottom, right-side perspective view of a keyboard including a control bar.

FIG. 2 is a bottom plan view of the keyboard shown in FIG. 1;

FIG. 3 is a top plan view of the keyboard shown in FIG. 1; FIG. 4 is a left-side elevational view of the keyboard shown in FIG. 1;

FIG. 5 is a right-side elevational view of the keyboard shown in FIG. 1;

FIG. 6 is a front elevational view of the keyboard shown in FIG. 1; and,

FIG. 7 is a rear elevational view of the keyboard shown in FIG. 1.

The broken lines immediately adjacent the shaded area represent the bounds of the claimed design while all other broken lines are directed to environment and are for illustrative purposes only; the broken lines form no part of the claimed design.
